(57) **CLAIM**

The ornamental design for an electrical card-edge connector, as shown and described.

DESCRIPTION

This application is related by subject matter to U.S. Design patent application entitled “Electrical Card-Edge Connector” filed on even date herewith under Ser. No. 29/363,269, and U.S. Design patent application entitled “Electrical Card-Edge Connector” filed on even date herewith under Ser. No. 29/363,270.

FIG. 1 is a bottom, left, front perspective view of an electrical card-edge connector according to my design;

FIG. 2 is a top, right, rear perspective view thereof;

FIG. 3 is a rear elevation view thereof;

FIG. 4 is a top plan view thereof;

FIG. 5 is a front elevation view thereof;

FIG. 6 is a bottom plan view thereof;

FIG. 7 is a left side elevation view thereof; and,

FIG. 8 is a right side elevation view thereof.

The broken line portion of the figures is included to show unclaimed subject matter only and forms no part of the claimed design. Only shaded areas shown in the drawing views are part of the claimed design.

In a preferred embodiment, the nature of this product is an electrical card-edge connector in the form of an electrical connector housing that retains a plurality of electrical contacts, such that the electrical card-edge connector is configured to mount to a first circuit board and mate with a second circuit board.
